UNITED STATES PATENT OFFICE

110,304

DESIGN FOR A PACKAGE DISPENSER

Gordon W. Knipple, Chicago, Ill., and Nathan L. Mercer, Marengo, Iowa

Application February 28, 1938, Serial No. 75,476

Term of patent 3½ years

To all whom it may concern:

Be it known that we, Gordon W. Knipple, a citizen of the United States, residing at Chicago, in the county of Cook and State of Illinois, and Nathan L. Mercer, a citizen of the United States, residing at Marengo, in the county of Iowa, State of Iowa, have invented a new, original, and ornamental Design for Package Dispensers, of which the following is a specification, reference being had to the accompanying drawing, forming part thereof.

The single figure of the drawing is a view in perspective of a package dispenser showing our new design.

The undisclosed portion of the article is of substantially the same appearance as the portion shown.

We claim:

The ornamental design for a package dispenser as shown and described.

GORDON W. KNIPPLE.
NATHAN L. MERCER.
